AND PRODUCT STORAGE AND DISPLAY
UNIT**

Guilbert M. Hunt, 110 E. 293rd St., Willowick, Ohio

Filed Mar. 13, 1962, Ser. No. 69,236

Term of patent 14 years

(CL. D52—2)

FIGURE 1 is a front elevational view of a combination dual gasoline dispenser and product storage and display unit showing my new design.

FIGURE 2 is an end elevational view of the unit of FIGURE 1 as viewed from the left thereof.

FIGURE 3 is a front elevational view of a modified form of the unit showing my new design, without a canopy.

FIGURE 4 is an end elevation of the unit of FIGURE 3, as viewed from the left thereof.

The sides and ends opposite those shown in the figures are substantially the same as those shown in respective figures.

The essential features of the design reside in the portions shown in solid lines.

This application is a continuation-in-part application of my copending applications Serial Numbers D. 66,816 and D. 66,817 both of which were filed on September

22, 1961, and which have become abandoned since the filing of this application.

I claim:

The ornamental design for a combination dual gasoline dispenser and product storage and display unit, as shown and described.
